UNITED STATES PATENT OFFICE.

EDWARD F. SMITH, OF ROCHESTER, NEW YORK.

VEGETABLE-SLICER.

976,613.

Specification of Letters Patent. Patented Nov. 22, 1910.

Application filed November 19, 1908. Serial No. 463,458.

To all whom it may concern:

Be it known that I, EDWARD F. SMITH, a citizen of the United States, residing at Rochester, in the county of Monroe and

5 State of New York, have invented certain new and useful Improvements in Vegetable-Slicers, of which the following is a specification, reference being had therein to the accompanying drawing.

10 My invention relates to improvements in vegetable slicers.

The object of my invention is to provide a slicer of this character in which the knives are mounted upon rotary arms and are rotated on said arms in a direction opposite to the movement of the arms, whereby a sheathing cutting action, as well as a rotary cutting action is obtained.

Another object of my invention is to provide 20 a cutter of this character having many advantageous details of structure, and providing a more simple, cheap and effective cutter.

In the accompanying drawings, Figure 1, 25 is a side elevation, partly broken away, of my improved slicer. Fig. 2, is a top, plan view of Fig. 1. Fig. 3, is a side elevation showing the cutter tilted upon the legs, and showing a bottom plan view of the gage 30 plate, the cutting blades and its operating mechanism. Fig. 4, is a vertical sectional view taken on the line 4—4 of Fig. 3. Fig. 5, is a vertical, transverse, sectional view taken on the line 5—5 of Fig. 2. Fig. 6, 35 is a perspective view of the knife-carrying arm showing one end broken away. Fig. 7, is a perspective view of the gage plate partly broken away.

Referring now to the drawings, 1 and 2 40 represent the legs spaced the proper distance apart, and having at their upper ends the enlarged circular portions 3 and 4 which form enlarged bearing surfaces for the frame 5, and upon which the same is pivoted, 45 which I will now proceed to describe.

The legs at their lower ends are provided with feet 6 which are provided with openings through which bolts 7 pass, and by means of which the legs are secured to the 50 stand or other support. The inner faces 8 of the enlarged circular portions 3 and 4 are smooth and the knife and gage supporting frame 5 at opposite sides is provided with downwardly-extending ears 9 55 and 10 which are of the same size as the circular portions 3 and 4 and rest snugly

against the surface 8 and passing centrally through the ears and the enlarged portions are bolts or pivots 11 and 12 which are provided at their inner ends on the inside of 60 the ears with nuts 13 and 14, and on their outer ends on the outside of the circular portions 3 and 4 with nuts 15 and 16, whereby the frame 5 is pivotally supported between the legs and adapted to swing upon the 65 bolts.

In order to allow of locking the frame in its adjusted or oscillated position, whereby the legs can be attached to an uneven or slanting surface, and yet retain the frame 70 in a horizontal position, I provide the enlarged portion 3 with a pin 17 which extends inwardly through a slot 18 in the ear 9. By this arrangement it will be seen that the frame can be swung from a horizontal position to an oblique position past the vertical line, whereby the working of the knives and mechanism is exposed for cleaning and replacing or repairing any of the parts. In order to hold the frame in its adjusted position 75 I provide a set screw 19 which passes through the enlarged portion 3 and engages the inner face of the ear 9.

The frame 5 consists of a circular plate 20 having the laterally-turned upper ends 21 85 and 22 of the ears 9 and 10 bolted thereto by means of the bolts 23. The plate 20 on its lower face is provided with a downwardly-extending cutting edge 82 surrounding the opening, and the same being formed integral 90 with the plate. The arch-shaped member 24 is also secured to the frame 20 by means of the bolts 23, and is preferably of the form shown in Fig. 1. The said member 24 adjacent one side is provided with the downwardly-extending portion 25 having an enlarged horizontal bearing 26 at its lower end. Mounted in said bearing is a horizontal shaft 27 which extends outward through a bearing 28 in the arch 24, whereby the shaft is held against twisting. On the outer end a crank 29 is provided, by means of which the shaft is rotated, but preferably I employ a balance or fly wheel shown in dotted lines, Fig. 2 and indicated 100 at 30. The inner end of the shaft 27 has secured thereon a beveled gear 31 which is preferably provided with an elongated sleeve 32 held upon the shaft by the set screw 33. The inner end of the sleeve bears 105 against the bearing 26 and prevents the outward movement of the shaft. In order to

prevent the inward movement of the shaft I provide a collar 34 held upon the shaft by the set screw 35.

The arch 24 at the center is provided with 5 a vertical bearing 36 in which is rotatably mounted a shaft 37 having at its upper end a cap or collar 38 held thereon by a set screw 39, whereby the downward movement of the shaft is limited. The shaft below the bearing 36 is provided with a sleeve 40 held upon the shaft by a set screw 41 and which limits the upward movement of the shaft. The lower end of the sleeve is provided with a beveled gear 42 meshing with the beveled gear 31, whereby the shaft 37 is rotated. The cross-head 42' is provided on its lower face with a sleeve 43' rigidly carried by the cross-head. The lower end of the shaft 37 extends through the opening 44' in the cross-head and extends into said sleeve and is locked therein by the set screw 45'. The said cross-head is provided with the two curved arms 43 and 44 oppositely arranged.

The outer ends of the arms are curved outwardly as indicated at 45 and provided with the enlarged corrugated fan-shaped ends 46 which are concaved to receive the gears as will be hereinafter more fully described. The outer ends of the arms are provided 25 with openings 47 in which are rigidly secured the shafts 48 held in said openings by set screws 49, and loosely mounted upon the upper end of the shaft are disk cutters 50 and 51. Secured to the lower face of the 30 cutters is a gear 52 rigidly held upon the blade by means of the screws 53, and said gear rotates in the concaved portion of the arms 43 and 44. The outwardly curved portion 45 of the arms is provided with an 35 opening 54 in which is mounted the shaft 55 of the idle gear 56 meshing with the gear 52.

Loosely mounted upon the shaft 37 is a sleeve 57 which has at its lower end a gear 59 rigidly attached thereto which meshes 45 with the idle gear 56, whereby the rotation of the gear 59 rotates the knife in the same direction through the idle gear. The upper end of the sleeve has secured thereon by means of a screw 60 a beveled gear 61 meshing with the lower edge of the beveled gear 31, and whereby it is rotated in the opposite direction to the gear 42. By this arrangement it will be seen that the knives travel around beneath the frame 20 and are 50 at the same time rotated in the opposite direction of said travel, whereby a shearing action is obtained.

The frame 20 is provided with openings 62 of different sizes and shapes, and surrounding the same opening upon the upper face of the frame are the pockets 63 which are adapted to hold the vegetables being cut as said vegetables are fed by gravity to the cutters. In some instances specially shaped 60 pockets are provided which removably fit

within opening 52, whereby the vegetables cut may be held in the proper position.

In order to vary the thickness of the slices to be cut, I provide a gage plate 64 which is of a disk form and of a size approximately 70 the size of the frame 20 and provided with openings 65 and 66 in which the knives are rotated. The outer edge of the gage plate is provided with the downwardly-extending corrugated flange 67 which prevents the 75 slices from being thrown outwardly after being cut. The gage plate is provided with a central depressed portion 68 into which the central gear 59 extends and rotates. Said depressed portion is provided with a 80 downwardly-extending cylindrical housing 69 formed integral with the depressed portion 68, and said gage plate is cut away as indicated at 70, so as to allow the arms 42 carrying the knives to extend therein, whereby 85 the gage plate is rotated with the arms. The sleeve 43' extends within the cylindrical housing 69 and the set screw 45 passes through the slot 70 in the housing, whereby the gage plate is further locked upon the 90 sleeve or arms, and yet, owing to the slots it is allowed vertical movement. In order to support the gage plate upon the sleeve and provide means for adjusting it up and down to regulate the thickness of the slice, 95 I provide the lower end of the housing with a plate 71 secured thereon by screws 72. The said plate is provided with a keyhole slot 73 through which the thumb-screw 74 passes, having a groove 75 by means of 100 which the screw is swiveled to the plate 71, and by means of the keyhole slot the thumb-screw can be removed. The screw 74 extends upwardly and is screwed into the lower end of the shaft 37, whereby the gage 105 plate is moved up and down to regulate the thickness of the slice.

The curved portion 45 of the arms 43 and 44 throws the gear to one side and thus allows a larger gear 59 and causes a more 110 rapid rotation of the knives without increasing the length of the arms. The fan-shaped portion 46 of the arms not only forms a shield for the gear, but also forms a brace for the cutters or cutting disk as the 115 cutters rest upon the upper smooth surface and brace the blades adjacent their outer cutting edge.

In order to provide means for sharpening the blades without removing the same, or any of the other operative parts, I provide the lower face of the gage-plate adjacent each cutting disk with a downwardly-extending stud 76 upon which is provided the arm 77. The outer end of the arm carries 120 a grinding substance as indicated at 78. Secured to the gage plate adjacent the stud 76 is a leaf-spring 79 which normally bears against the flat side 80 of the arm 77, and holds the same in the position shown in 125 130

Fig. 7. When it is desired to sharpen the disks the arm 77 is swung upwardly, the spring engaging the flat end 81 of the arm holding the arm in approximately a vertical position with the grinding substance 78 against the cutting disk, and by operating the crank the blades or disks are sharpened.

The operation of the machine is as follows: The crank 29 is operated which rotates the shaft 27 which in turn rotates the beveled gear 31. This beveled gear in turn rotates the beveled gear 42 and through the medium of the sleeve 40 which is locked to the shaft 37, the same is rotated in one direction while the arms 43 and 44 are rotated in the direction of the arrows shown in Figs. 2 and 3. This causes the knives to travel under the frame 20 supporting the pockets and to cut the contents in coöperation with the extended cutting edge 82 carried by the lower face of the frame. The beveled gear 31 engaging the beveled gear 61 is rotated in the opposite direction to the shaft 37, and by means of the gears 59, 56 and 52 the cutters are rapidly rotated in the same direction as the gear 51, as shown by the arrow in Figs. 2 and 3. In order to regulate the thickness of the cut the gage plate is adjusted up or down by the thumb screw 74 which brings the plate farther away from or closer to the knives and allows the contents of the pockets to drop farther down, or not so far, to regulate the thickness of the slice, as the gage plate serves as a support for the contents of the pockets.

Having thus described my invention, what I claim and desire to secure by Letters Patent, is:—

1. A slicing machine comprising a frame, a rotary arm carried by the frame, a rotary knife carried by the outer end of the arm, a rotary gear carried by the frame and rotating in opposite direction to that of the arm, a gear carried by the knife and an intermediate gear meshing with said gears.

2. A slicing machine comprising a frame, a rotatable arm carried by the frame, means for rotating the arm, a rotary knife carried by the arm, a rotatable gear carried by the frame, means for rotating the gear in a direction opposite the rotation of the arm, a gear carried by the knife and an intermediate gear carried by the arm and meshing with said gears.

3. A slicing machine comprising a frame, a vertical shaft therein, an arm carried by the shaft, means for rotating said shaft, a gear loosely mounted upon the shaft, means for rotating the gear in a direction opposite the rotation of the shaft, a gear carried by the knife, a gear carried by the arm and meshing with said gears.

4. A slicer comprising legs, a frame pivotally supported by said legs, means for locking the frame in its adjusted position,

a rotary arm below the frame, a rotary cutter carried by the outer end of the arm, and means for rotating the arm in one direction and rotating the knives of the arm in the opposite direction, and a gage plate carried by the arm for regulating the thickness of the slice.

5. A slicer comprising legs, a frame between the legs and having pivots mounted in the legs, a set screw carried by one leg and engaging the frame for holding it in its adjusted position, means for limiting the oscillating movement of the frame, an arm rotatably supported by the frame adjacent the lower face, a cutter rotatably supported upon the upper face of said arm, and means for rotating the arm and rotating the knife on the arm in a direction opposite to the movement thereof.

6. A slicer comprising legs, a frame between the legs and having pivots mounted in the legs, pins rigidly carried by the legs and extending inwardly into a segmental slot in the frame to limit the movement of the frame, a set screw extending through one leg and engaging the frame for locking the same in its adjusted position, an arm rotatably supported below the frame, a knife rotatably supported by the arm, means for rotating the arm, means for rotating the knife in an opposite direction to the movement of the arm, a circular gage plate having openings to receive the knife, and means for vertically adjusting said plate for regulating the thickness of the slice.

7. A slicer comprising a frame having openings therein, shearing edges surrounding the openings on the under side of the frame, an arm rotatably supported below the frame, a knife rotatably supported by the outer end of said arm, a gear carried by the knife, an idle gear carried by the arm and meshing with the first mentioned gear, and a gear loosely mounted upon the pivot of the arm and meshing with the idle gear, means for rotating the last mentioned gear, and means for rotating the arm, substantially as shown.

8. A slicer comprising a frame having openings therein, a yoke carried by the frame, a shaft having its upper end mounted in said yoke and its lower end extending through the frame, a beveled gear for rotating the shaft, an arm rigidly carried by the shaft below the frame, a rotary knife mounted upon the upper face of the arm at its outer end, a sleeve loosely mounted upon the shaft and having a beveled gear above the frame directly below the beveled gear on the shaft, a beveled gear between the two beveled gears and driving the same in opposite directions, a gear carried by the lower end of the sleeve, an idle gear mounted upon the arm and meshing with said gear, and a gear rigidly carried by the knife and mesh-

ing with the idle gear, whereby the arm is revolved in one direction and the knife rotated thereon in the opposite direction.

9. A slicing machine, comprising a frame, 5 a rotary arm, a rotary knife carried by the outer end of said arm, a rotary gear carried by the frame and driven in the opposite direction to that of the arm, a gear carried by the knife, an intermediate gear meshing 10 with said gears and a gage plate supported by the arm and movable independent thereof.

10. A slicing machine, comprising a frame, a rotary arm carried by the frame, a rotary knife carried by the outer end of 15 the arm, a gear carried by the frame, a gear carried by the knife, an intermediate gear carried by the arm and meshing with the said gears and a gage plate surrounding the knife and supported by the arm and 20 movable independent thereof.

11. A slicer comprising a round frame, a yoke carried by the upper face thereof, a vertical shaft supported by the yoke and extending through the frame, an arm carried 25 by the lower end of said shaft, knives carried by the arm, a gearing loosely mounted upon the shaft and driving said knives, and means mounted upon the yoke for rotating the shaft in one direction and the 30 gear in the opposite direction, whereby the knife is rotated in a direction opposite to the movement of the arm.

12. A slicer comprising a round frame, a yoke carried by the upper face thereof, a vertical shaft supported by the yoke and 35 extending through the frame, an arm carried by the lower end of the shaft, knives carried by the outer ends of the arm, a gearing loosely mounted upon said shaft 40 and driving said knives, means mounted in the yoke for rotating the shaft in one direction and the gear in the opposite direction, a gage plate of a circular form having openings to receive the knives, and means for 45 vertically adjusting the gage plate upon the arm.

13. A slicer comprising an oscillating frame, a yoke carried thereby, a shaft supported in the yoke and extending down 50 through the frame, means for rotating said shaft, an arm secured at its center to the lower end of the shaft, a gear loosely mounted upon the shaft above the arm, an idle gear carried by the arm on opposite sides 55 of the gear and meshing therewith, a rotary knife supported in the outer ends of said arm, a gear carried by each knife and meshing with the idle gears, means for driving the gear loosely mounted upon the shaft 60 in a direction opposite to the shaft, a gage plate having a central depressed portion adapted to receive the shaft, a plate closing the lower end of said cylindrical portion having a keyhole slot therein, a thumb-screw 65 screwed into the shaft and having an annu-

lar groove in which the plate rests, whereby the gage plate is vertically movable.

14. A slicer comprising legs, a circular plate having openings therein, downwardly turned ears carried by opposite sides of the 70 plate and having pivots carried thereby and mounted in the legs, pockets bolted to the upper face of the plate and surrounding the opening, a downwardly-extending flange surrounding the opening on the lower face 75 of the plate to form a shearing surface, a rotary arm revolving below the plate and disk knives rotatably mounted upon said arm and having shearing action with the flange of the plate. 80

15. A slicer comprising a frame, having openings therein, pockets above the openings, a flange carried by the under side of the frame and surrounding the opening, an arm rotatably mounted below the frame 85 disk knives rotatably mounted upon the arm, means for rotating the knives in a direction opposite to the movement of the arm, a gage plate supported by the arm, means for vertically adjusting said gage plate, and 90 pivoted knife sharpening means carried by the lower face of the gage plate and adapted to be swung in engagement with the knife and a spring for holding the sharpener in or out of engagement with the knife. 95

16. A slicer comprising a frame, a shaft supported by the frame, an arm secured to the lower end of the shaft, a gear loosely mounted upon the shaft above the arm, an idle gear carried by the arm and meshing 100 with said gear, a rotary knife supported by the outer end of said arm a gear carried by the knife and meshing with the idle gear, and means for rotating said gears and shaft. 105

17. A slicer comprising a frame, a shaft 110 supported by the frame, an arm secured to the lower end of the shaft, a gear loosely mounted upon the shaft, means for rotating the shaft in one direction, means for rotating the gear in the opposite direction to the 115 shaft, an idle gear carried by the arm and meshing with the before mentioned gear, a knife rotatably mounted in the outer end of the arm, and a gear carried by the knife and meshing with the idle gear. 115

18. A slicer, comprising a frame, a shaft supported thereby, an arm secured to the lower end of the shaft, a gear loosely mounted upon the shaft, a knife rotatably mounted in the center of the end of the arm, a 120 gear carried by the knife, the arm having an off-set portion intermediate the gears, and an idle gear loosely mounted in said offset portion and meshing with said gear.

19. A slicer, comprising a frame, a shaft 125 supported thereby, an arm secured at its center to the lower end of the shaft, a gear loosely mounted upon the shaft above the arm, means for rotating the shaft, means for rotating the gear in the opposite direc- 130

- tion, an idle gear carried by an arm on opposite sides of the gear and meshing therewith, rotary knives supported in the outer ends of said arms, a gear carried by each 5 knife and meshing with the idle gear, a gage plate having a central depressed portion adapted to receive the shaft, a plate closing the lower end of said cylindrical portion, a thumb screw swiveled to said 10 plate and screwed into the shaft, whereby the gage plate is removed vertically.
20. A slicer comprising a frame, a yoke carried thereby, a vertical shaft supported in the yoke and extending down through 15 the frame, a horizontal shaft mounted in the yoke, a beveled gear carried by the inner end of the shaft, a beveled gear carried by the upper end of the vertical shaft and meshing with the beveled gear above the 20 horizontal shaft, a sleeve loosely mounted upon the shaft, a beveled gear carried by the upper end of the sleeve and meshing with the beveled gear of the horizontal shaft, a gear carried by the lower end of the sleeve, 25 an arm secured at its center to the lower end of the shaft, an idle gear carried by the arm on opposite sides of the gear and meshing therewith, rotary knives supported in the outer ends of said arms, a gear carried 30 by each knife and meshing with the idle gear, and a gage plate vertically adjustable carried by the lower end of the shaft.
21. A slicing machine comprising a frame, a rotary shaft mounted therein, an arm 35 rigidly carried by the lower end of the shaft, a rotary knife carried by the outer end of said arm, a sleeve loosely mounted on the shaft, a crank adapted to rotate the shaft and sleeve in opposite directions, and means 40 carried by the lower end of the sleeve for rotating the knife carried by the arm.
22. A slicing machine comprising a frame, a rotary shaft mounted therein, an arm rigidly carried by the lower end of the shaft, 45 a rotary knife carried by the outer end of
- the arm, a sleeve loosely mounted upon the shaft, a gear carried by the lower end of the sleeve, a gear carried by the knife, an intermediate gear carried by the arm and connecting said gears, and means for rotating 50 the shaft and sleeve in opposite directions.
23. A slicing machine, comprising a frame, a rotary shaft mounted therein, an arm rigidly carried by the lower end of said shaft, a rotary knife carried by the outer 55 end of the arm, a sleeve loosely mounted upon the shaft, means carried by the sleeve for rotating the knife in an opposite direction to the rotation of the arm, beveled gears carried by the upper ends of the shaft and 60 sleeve and spaced a distance apart, a beveled gear between said gears and meshing therewith and a crank for rotating said gear.
24. A machine of the character described, comprising a frame a shaft supported thereby, an arm secured at its center to the lower end of the shaft, a gear loosely mounted upon the shaft above the arm, an upwardly extending sleeve rigidly carried by the gear, a beveled gear carried by the upper end of 65 the sleeve, a beveled gear rigidly carried by the shaft, a driven beveled gear between the first mentioned gears and meshing therewith and driving them in opposite directions, an idle gear carried by the arm on opposite 70 sides of the loose gear and meshing therewith, rotary knives supported in the outer end of said arms, a gear carried by each 75 knife and meshing with the idle gears, a gage plate having a central depressed portion adapted to receive the shaft, and locked to the arm against rotation, and means for vertically adjusting said plate on the shaft to move it to or from the knives.

In testimony whereof I affix my signature 85
in presence of two witnesses.

EDWARD F. SMITH.
